No. 819,232.

PATENTED MAY 1, 1906.

W. O. LEE.
SLEEPING GARMENT OR PAJAMAS.
APPLICATION FILED NOV. 22, 1904.

Fig. 1.

Fig. 3.

Fig. 2.

Witnesses:

J. Gruibner Jr.
F. A. Voehl.

Inventor

Walter O. Lee

by A. B. Wilcox & Co.

Attorney

UNITED STATES PATENT OFFICE.

WALTER O. LEE, OF NEW YORK, N. Y.

SLEEPING-GARMENT OR PAJAMAS.

No. 819,232.

Specification of Letters Patent.

Patented May 1, 1906.

Application filed November 22, 1904. Serial No. 233,897.

To all whom it may concern:

Be it known that I, WALTER O. LEE, a subject of the King of Great Britain, residing at New York, in the county of New York and State of New York, have invented certain new and useful Improvements in Sleeping-Garments or Pajamas; and I declare the following to be a full, clear, and exact description of the invention, such as will enable others skilled in the art to which it appertains to make and use the same.

My invention relates to improvements in pajamas and similar garments for sleeping and lounging purposes.

The object of the invention is to provide a one-piece garment of this character which will have the appearance of the usual two-piece garment or suit and in which the greatest convenience and comfort will be secured to the wearer.

With the above and other objects in view the invention consists of certain novel features of construction, combination, and arrangement of parts, as will be hereinafter described and claimed.

In the accompanying drawings, Figure 1 is a perspective view of my improved garment, showing the same in its opened position. Fig. 2 is a detail vertical sectional view through the waist portion of the garment; and Fig. 3 is a view similar to Fig. 1 of a slightly-modified form of the invention, parts being broken away to more clearly illustrate the construction.

Referring to the drawings by numerals, 1 denotes the jacket or coat, and 2 denotes the trousers, which are united to the jacket to form a one-piece suit or garment, as shown. The jacket and trousers may be made of any material and in any style, and they may be made separate and then united, as shown in Figs. 1 and 2, or integral of one or more vertical strips of material, as shown in Fig. 3. In either case the trousers are open around the crotch 3 from the front of the waist to its rear, so that the two legs 4 are independent of each other, and the jacket is open at the front to permit of the garment being put on and off. The front of the jacket and also the fly or front of the trousers may be held together or closed by providing buttons 5 and buttonholes 6, as shown, or any other suitable fastening means. If desired, tabs 11 may be employed at the front of the waist of the trousers, as shown.

As shown in Figs. 1 and 2, the jacket and trousers are made separate, and the upper edge or waist of the trousers is sewed, as at 7, or attached in any other suitable manner to the inner face of the lower part of the jacket, 6c which latter is made long to form a surrounding skirt 8 to cover and conceal the opening 3 in the trousers.

In Fig. 3 of the drawings the body of the jacket and the legs of the trousers are shown as formed from one continuous strip or piece of fabric or other material, and the skirt is formed by a separate piece or band of material 9, which is sewed or otherwise secured, as at 10, upon the outside of the garment at its 70 waist, so that it hangs down and hides the opening in the trousers.

The advantages of the invention will be readily understood from the foregoing description, taken in connection with the accompanying drawings. The open portions of the jacket and trousers enable the garment to be readily put on and off, and there are no draw-strings or other tight connections at the waist. The entire body is covered by the garment, and the hanging skirt portion covers and protects the opening in the trousers, so that the modesty of the ordinary garment is preserved.

When the garment is made for the use of women, the skirt may be made as long as desired.

Various changes in the form, proportion, and the minor details of construction may be resorted to without departing from the principle or sacrificing any of the advantages of this invention as defined by the appended claims.

Having thus described my invention, what I claim as new, and desire to secure by Letters Patent, is—

1. A garment of the character described comprising the united jacket and trousers, the latter being open around the crotch from the front to the rear of the waist, and the former having a skirt secured on the outside and adapted to conceal the opening in the trousers, substantially as shown and described.

2. A garment of the character described comprising a jacket and trousers, the body of the former and the legs of the latter being formed of a continuous strip of material, said trousers being open around the crotch from the front to the rear of the waist, and a surrounding skirt attached to the garment on the outer side at the waist and depending therefrom to conceal said opening in the trousers, substantially as shown and described.

WALTER O. LEE.

Witnesses:

CLAUDE B. WEVER,
WM. LESTER WEMPLE.